(57) **CLAIM**

The ornamental design for a “thermal paste syringe”, as shown and described.

DESCRIPTION

FIG. 1 is a top front right perspective view of a thermal paste syringe showing my new design;

FIG. 2 is a top rear right perspective view thereof;

FIG. 3 is a bottom front left perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof, and,

FIG. 9 is a bottom view thereof.

The dashed broken lines illustrate environmental structure and form no part of the claimed design.
